UNITED STATES PATENT OFFICE.

FRANK W. KRAMER, OF PORTLAND, OREGON.

ADJUSTABLE BED.

1,108,502.

Specification of Letters Patent. Patented Aug. 25, 1914.

Application filed November 20, 1911, Serial No. 661,283. Renewed February 12, 1914. Serial No. 818,371.

To all whom it may concern:

Be it known that I, FRANK W. KRAMER, a citizen of the United States, residing at Portland, in the county of Multnomah and State of Oregon, have invented certain new and useful Improvements in Adjustable Beds, of which the following is a specification.

This invention relates to improvements in adjustable beds, and has for its object to provide a bed which can be collapsed into small compass and which can be raised and lowered within certain limits.

A further object is to arrange a central seat or support which can be adjusted to regulate the tension, or prevent sagging of the bed springs.

A further object is to construct a bed which may readily be converted into a cot or chair. The frame work is made preferably of angle iron for economy and strength, which material also makes the article sanitary.

These and other objects are attained by the mechanism illustrated in the accompanying drawing, in which—

Figure 1 is a side elevation of the bed arranged in the form of a chair. Fig. 2 is a partial sectional elevation, showing the auxiliary seat or support, in detail. Fig. 3 is a view of the releasing mechanism for the supporting bars for the hinged members. Fig. 4 is a perspective detail of the mechanism for holding the bed spring in place, in the member raised to form the back of the seat. Fig. 5 is a view of a similar device for holding the front portion thereof in place. Fig. 6 shows a modified form of supporting bar or frame, by means of which the improvement is adapted for use on ordinary beds. Fig. 7 is a detail view of a supporting brace, for the swinging members, showing the manner in which said members may be locked at any desired point, and the means by which they are released.

Referring to the drawings in detail, 1 represents the outwardly inclined legs of the frame work, having the intermediate horizontal portion 1^a, the legs being united by the brace 2. Each pair of legs is united to the other by the cross brace 28 held in place by the bolts 27. Upon the portion 1^a, by means of bolts 26, is mounted the body 3 of the bed, having the transverse portion 3^a. The vertical portions are provided with apertures 23, so that the body

may be raised and lowered upon said bolts 26, to any distance desired.

At the upper end of each portion 3 is fixed a transverse bar 8 which carries at 60 one end a pivot pin 19, and at the other a similar pin 18. Upon the pins 19 is hinged the member 7 and to the opposite end is pivoted the member 9. Each side of the swinging members is provided with a pivot pin 65 15, carrying a brace or support 16, which enters a slot 29 in its corresponding upright portion, or frame 3, and which is provided in its lower edge with a series of notches 17, for engaging the angle iron 3.

The members 7 and 9, when the device is used as a bed, will be supported in horizontal position at 7^a and 9^a respectively. When the occupant desires to assume the sitting posture the member 7 is lowered by rocking the crank 24, of the shaft 30, which carries the wings 31, upwardly against its corresponding brace 16, lifting it from its engagement, as seen at 16^a in Fig. 3, and allowing it to descend through its slot 29, 70 over the inclined surface of the wing. When the member 7 has been lowered to the desired point the wings 31 will be dropped permitting the braces to again engage the irons 3 by means of said notches 17. The 75 member 9 at the same time may be raised, as seen in Fig. 1, to form the back of a chair. Each member is provided near its middle point with a support or stay, such as the chain 36, having the intermediate spring 90 37, and secured to the body portion at 38. This stay causes the members to be brought to their upward limit gradually and prevents them from being thrust too far forward. It will be seen that the stay will be 95 suspended loosely when the member is in horizontal or lower position and that it will be brought into action only when raised a considerable distance above that point.

An additional support is provided for the 100 braces 16, when in elevated position, in the bars 20, which are secured upon the bolts 22 in the upper portion of the body 3, and which carry at their ends the engaging bolts 21. These bars may be transposed so as to 105 project in the opposite direction from that shown in Fig. 1, when it is desired to support the member 7 in an elevated position, so that either end may be used as back or front. The curved portion 16^a of the braces 110 16 allows the members 7 and 9 to swing to a vertical position without binding in

their slots; and the downwardly inclined tip 16^a prevents the brace from dropping from its slots and it rests upon the wing 31 in readiness to be released by crank 24 when 5 the member is to be lowered.

Interposed between the vertical end pieces 3 are transverse bars 14, adjustably held against the vertical supports 4 in apertures 10, by means of bolts 5. The upright 4 is 10 secured to the cross bars 6, which in turn are supported upon the frame 3. Upon these bars 14 are secured springs 11 carrying the seat 12, which is covered by the pad 13. The adjustment of the bar 14 in apertures 10 permits the seat to be so disposed as 15 to prevent sagging of the bed spring; and its springs and pad allow it to yield sufficiently to be always comfortable.

As seen in Figs. 4 and 5, the wire web 20 consists of the springs 31, secured by one end in the flanges 7^a, 8^a and 9^a respectively of the angle irons 7, 8 and 9, the other ends being secured in rings 32, in which are anchored the intervening longitudinal wires 33 and 25 the cross wires 34. Stays 35 engaged in the bar 6 are secured in rings 32 above each edge of the body portion 3, so as to hold the bed spring in position along that line when the end members are raised above the horizontal. 30

In Fig. 6 is shown a modification in which my improved device is adapted for use on the common bedstead. The rails 1st carried by brackets 39, secured on the posts 40, have 35 formed in proper position, near their middle points suitable apertures in which are engaged the bolts which support the frames 3, which are adjustably carried there, as in the case above described. When the bed is completely collapsed the members 7 and 9 will 40 be dropped down against the body 3, as at 7^b and 9^b, and the body will be lowered on the pins 26. In this case the member 9 is shown slightly longer than member 7, but it 45 is obvious that the relative lengths may be varied to suit individual wishes.

Having thus described my invention, what I claim, is—

1. In a bed comprising a frame, an intermediate body section vertically adjustable therein, a spring pad vertically adjustable in the body section, end members hinged to said section and independently adjustable

thereon, and braces pivotally secured upon the end members and slidably engaged in 55 the body section, whereby the end members may be secured at any desired angle with reference thereto.

2. A bed comprising a frame, an intermediate body section vertically adjustable 60 therein, a spring pad vertically adjustable in the body section, end members hinged to said section and independently adjustable thereon, braces pivotally mounted upon the end members and adjustably engaged in the 65 body section, whereby the end members may be secured at any desired angle with reference thereto, and means for yieldingly limiting the upward movement of said end members. 70

3. A bed comprising a frame, an intermediate body section vertically adjustable therein, a spring pad vertically adjustable 75 in the body section, end members hinged to said section and independently adjustable thereon, braces having spaced notches along their lower edges pivotally secured upon said members and adapted for adjustable engagement in said body section, each of said braces terminating in an irregular curve 80 whereby the end members are permitted to be raised to a vertical position, when the braces will engage in said body section to limit such movement.

4. A bed comprising a frame, an intermediate body section vertically adjustable 85 therein, a spring pad vertically adjustable in the body section, end members hinged to said section and independently adjustable thereon, braces having spaced notches along 90 their lower edges, pivotally mounted on said members and adapted for adjustable engagement in said body section, whereby the end sections may be secured at any desired angle 95 with reference to the body section, and means mounted on the body section for holding said braces from engagement therein during the downward movement of the end members.

In testimony whereof I affix my signature 100 in presence of two witnesses.

FRANK W. KRAMER.
